United States Patent Office.

CHARLES S. BALDWIN, OF NEW YORK, N. Y.

Design No. 3,895, dated March 15, 1870.

DESIGN FOR AN ARTIFICIAL FLOWER.

The Schedule referred to in these Letters Patent and making part of the same

To all whom it may concern:

Be it known that I, CHARLES S. BALDWIN, of the city of New York, in the county and State of New York, have invented and produced a new and original Design and Pattern, of original shape and configuration, for the Manufacture of "Artificial Flowers; and I do hereby declare that the following is a clear, full, and exact description thereof, reference being had to the accompanying drawings and description, and to the letters of reference marked thereon making a part of this specification.

The nature of my invention and design consists of a piece of muslin marked No. 1, of triangular shape, with five scallops on the base end.

No. 2 consists of a round piece of muslin, with said scallops of triangular shape, and hole in the center.

No. 3 consists of a piece of thin muslin, of triangular shape, with six scallops on the base end.

No. 4 consists of seven-thread stem, with yellow muslin brush-shaped heads.

No. 5 consists of a small wire stem, covered with paper and with a glass cap, running through and forming the stem of the flower when put together.

No. 6 consists of a muslin leaf, with seven scallops on each side of the center stem, and one scallop on the top end of the configuration or leaf.

Claim.

What I claim as my invention, and desire to secure by Letters Patent, is—

The design or pattern for an artificial flower, herein set forth.

C. S. BALDWIN.
